(57) **CLAIM**

The ornamental design for a curved computer, as shown and described.

DESCRIPTION

FIG. 1 is a perspective view of a curved computer showing my new design;

FIG. 2 is a back side elevation view thereof;

FIG. 3 is a Front side elevation view thereof;

FIG. 4 is a Left side elevation view thereof;

FIG. 5 is a Right side elevation view thereof;

FIG. 6 is a Top plan view thereof;

FIG. 7 is a Bottom plan view thereof; and,

FIG. 8 is a top plan view thereof with the curved display shown opened.

Broken lines shown in the drawings illustrate portions of the curved computer and form no part of the claimed design.
